United States Patent Office

Des. 185,572
Patented June 23, 1959

185,572

GAME BOARD

Homer M. Rockwell, San Francisco, Calif.

Application May 28, 1958, Serial No. 51,115

Term of patent 14 years

(Cl. D34—5)

The figure illustrates a top plan view of a game board, showing my new design.

The game board is of conventional thickness.

I claim:

The ornamental design for a game board, substantially as shown and described.
